UNITED STATES PATENT OFFICE.

WILHELM NORRES, OF SCHALKE, GERMANY.

ELECTRIC MINE-EXPLODER.

SPECIFICATION forming part of Letters Patent No. 707,626, dated August 26, 1902.

Application filed March 28, 1902. Serial No. 100,455. (No model.)

To all whom it may concern:

Be it known that I, WILHELM NORRES, a subject of the King of Prussia, German Emperor, and a resident of Schalke, Westphalia, in the Kingdom of Prussia, German Empire, have invented certain new and useful Improvements in Electric Mine-Exploders, of which the following is a full, clear, and exact description.

The present invention relates to electric mine-exploders in which, instead of the long conducting-wires being used till now and attached proximately to the mine-exploders and by means of which the transport and the dry preservation of the mine-exploders was rendered rather difficult, short metal pipes are provided within the firing-stopper containing the fuse composition, the conducting-wires being inserted into the said metal pipes; but then when the mine-exploder is to be put in action the said metal pipes are pinched together, thus being combined with the said conducting-wires, respectively, and with the mine-exploder. Furthermore, the explosive-shells of the present mine-exploder are divided on their open edge by means of incisures into several tongues, by means of which the said shells are simply set upon the conical firing-stopper without pinching the same upon the latter. In consequence of the aforesaid arrangement of the mine-exploder a more simple actuating of the same than hitherto will be obtained.

The electric mine-exploder is shown in the accompanying drawings, in which—

Figure 1 is a longitudinal section, and Fig. 2 a side view, of the same. Fig. 3 is an end elevation of the firing-stopper, and Fig. 4 an end elevation of the explosive-shell.

Within the conical firing-stopper *a*, which contains the fuse composition *b*, two metal pipes *c* are fixed, projecting into the latter

and closed at their inner ends. The explosive-shell *d* is provided at its open edge with incisures *f*, by means of which the edge is divided into several tongues, so that the explosive-shell may be simply set upon the conical firing-stopper *a*, whereby the tongues of the explosive-shells are forced outward, thus pinching and fixing the explosive-shell on the stopper *a*. When the mine-exploder is to be used, the conducting-wires *g* are inserted into the metal pipes *c*, as shown in Fig. 1, whereupon they are fixed within the latter by pinching together the metal pipes on the said wires, thus rendering the mine-exploder ready for action.

It will be evident that this mine-exploder may be conveyed from one place to another and preserved much easier than those employed hitherto, which were provided with long conducting-wires. Furthermore, the present mine-exploder can be made ready for action very easily and without any great trouble and pains.

Having now described my invention, what I claim as new, and desire to secure by Letters Patent, is—

In an electric mine-exploder the combination with a conical firing-stopper *a* containing the fuse composition, of metal pipe *c* fixed within the said stopper, conducting-wires *g* inserted into the said metal pipes, and an explosive-shell having a splitted open edge by means of which the said shell is simply set upon the conical firing-stopper *a*, substantially as described.

In witness whereof I have hereunto set my hand in presence of two witnesses.

WILHELM NORRES.
